TIMING APPARATUS FOR GARMENT PRESSES AND THE LIKE

Robert J. Randall, East Orange, N. J., assignor to
 Reiss Manufacturing Corp., Jersey City, N. J., a
 corporation of Delaware

Application July 12, 1941, Serial No. 402,251

24 Claims. (Cl. 38—36)

The present invention relates to means for automatically controlling certain of the operations of an apparatus, such as a garment press or the like. A primary object of the invention is to provide means for automatically securing extreme accuracy in the commencement and duration of the operations and to eliminate, substantially entirely, the human factor in performing the timing of certain functions of the apparatus.

Although not confined to such use, the invention of the present application is primarily adapted for the control of pressing operations in a garment press used in the clothing manufacturing industry, for instance, in the operation known as canvas basting, as is more fully described and claimed in the copending application of Reiss & Billings, Serial No. 397,808, filed June 12, 1941. In practicing the method of that invention, it is of maximum importance that the initial pressing operation performed under the influence of steam heat be accurately controlled as to its duration, since if it is prolonged unduly beyond the optimum, the adhesive employed to secure the canvas or stiffening ply to the garment ply will be dissipated and will not properly perform its adhesive function, while if the steam is delivered for an insufficient period of time, the adhesive will be insufficiently softened, with equally bad results. In a method of that type, it is also important that a vacuum cooling step be employed for an accurately predetermined period of time immediately after the steam pressing operation; that the press be opened at the conclusion of the first vacuum operation and that the garment be subjected to a second vacuum cooling operation with the press open.

The invention of the present application provides a timer for automatically controlling these or equivalent operations of a garment press.

It is a further object of the invention to provide an apparatus for so controlling a garment press that a single workman may operate two presses. When the apparatus of the present invention is used, the operator simply places the garment upon the press buck, closes the head and presses a starting button, whereupon the press goes through its cycle of operations. Meanwhile, the operator is removing a pressed garment from a second press and placing a new garment therein. When he has finished the latter work, the first press will have been automatically opened and the garment therein completely pressed. Hence, the output of a single operator is substantially doubled by the present invention.

A further object of the invention is to provide

5 a timer for automatically controlling the operations of a garment press which does not interfere with the standard operator-actuated controls associated therewith, so that, without any changes, the press may be operated manually in accordance with old methods, if desired. This is advantageous, since certain garments require unusual pressing operations which can best be performed by a skilled operator using his judgment as to the time of duration of the various operations.

10 A further object of the invention is to provide a press timer that is automatically reset to a normal starting position upon completion of a normal cycle, or upon manual interruption of a cycle by the operator, for one reason or another. From the practical viewpoint, it is important that automatic reset means for the timer be provided, since, otherwise, if one cycle were interrupted before completion, the next cycle would start at an intermediate point, instead of at the normal starting point, and the operations would be entirely out of phase. In the absence of automatic resetting means, delicate adjustments would be necessary, to bring the timer back to its correct starting position.

15 It is essential that, in spite of the provision of timer controlled means for opening the press, operator-actuated means for performing this function remain operative, so that the operator may open the press at will. Occasionally, a garment is positioned on the press buck in wrinkled or bunched position and, if this circumstance is discovered after the head is closed, the operator 20 must be able to open the press immediately, to rectify the error. Moreover, as a safety factor, the operator must be able to open the press in the event that his hands or any other part of his body be inadvertently caught between the buck and the head. Further, should foreign objects, such as scissors or other tools be lodged between the buck and the head, it is important that the head be opened immediately by operator-actuated means.

25 As stated above, an important object of the present invention is to provide means permitting the operator to open the press at will and means actuated thereby for automatically resetting the timer to its normal starting position, so that the timer does not get out of phase with the desired press operations.

30 A further object of the invention is to provide novel power-actuated means for releasing the locking means for holding the head closed upon the buck, to permit the head to open. Preferably,

this head lock releasing means is operated by solenoid-actuated means controlled by the timer.

A further object of the invention is to provide novel solenoid-operated means for controlling the steam valve associated with a garment press head and to provide connections so arranged that manual operation and foot pedal operation of the steam valve are in no wise interfered with.

A further object of the invention is to provide similar solenoid-operated means for controlling the vacuum valve in the line leading to the press buck, without interfering with the normal operator-actuated control means therefor.

A further important object of the invention is to provide means for initiating the operation of the timer and the operations of the press only after the press head has been moved to and locked in closed position upon the buck, thereby preventing premature discharge of steam from the press head, or premature starting of other press operations.

Other and further objects and advantages of the invention will become apparent from the following description of the specific embodiments of the invention disclosed in the drawings.

In the drawings:

The apparatus of the present invention has been designed for use with garment presses of the Hoffman type, model "V," manufactured by U. S. Hoffman Machinery Corporation and, although not confined to use on presses of this type, in the accompanying drawings and in the following description, reference will be made thereto. The press comprises a base 10 having a pair of spaced, upwardly projecting side frame members 11, 12, integral therewith and carrying at their upper end a buck support 13 and a working table 14. From a rearwardly extending portion 10' of the base 10, there are a pair of upwardly projecting frame members 15, 16, terminating at their upper ends in rearwardly spaced relation to the buck 17. A heavy bifurcated lever 18, pivoted about the axis of a shaft 19, supported by the upper ends of the frame members 15, 16, carries a press head 20 at its forward end and a counter-weight 21 at its rear end.

A forwardly breaking toggle mechanism comprising a lower link 22 and parallel upper links 23 is connected between the rearwardly projecting portion of the lever 18 and a stub shaft 24 adjacent the rear of the base 10'. A second toggle mechanism comprising a link 25 connected to the first toggle at 26 and a second link 27, pivoted on a fixed axis 28 is provided for the purpose of straightening the first toggle, thereby closing the head upon the buck, the second toggle being operated by a downwardly projecting link 29 connected to a foot-operated pedal 30 pivoted to the sub-shaft 24 carried by the base of the machine. As is well understood in the art, pressure applied to the foot pedal 30 straightens the toggle links 25, 27, thereby straightening the first toggle links 22, 23 and applying pressure to the head upon the buck. Continued downward movement of the pedal urges the joint 32 between the toggle links 25 and 27 upwardly a slight distance past dead center, the movement being arrested by stop members 33, 34 carried by the toggle and the press frame, respectively. A tension spring assembly 35, connected between the pivot 28 and the upper end of link 23, assists the weight 21 in collapsing the toggles and opening the press head. Normally, the press head is opened by a kick-off pedal 37 (Fig. 1) pivoted on a transverse shaft 38 (Figs. 3 and 4) and having its rear end 39 underlying the main pedal 30. Hence, when the kick-off pedal 37 is depressed, the end 39 is raised, thereby raising the pedal 30 and the link 29 and swinging the toggle link 27 in a counter-clockwise direction, to move the joint 32 downwardly to below dead center, whereupon the spring 35 and the weight 21 collapse the toggles and raise the press head to open position.

As is well understood in the art, the upper end of the link 23 may be pivoted at 42 to one end of a bell crank lever 43, fulcrumed at 44 adjacent the rear end of the lever 18 and having its other end connected to a clevice 45, which has a threaded connection with an adjusting rod 46, the latter being connected at its forward end with a hand wheel 47 journalled in a transverse web 48 carried by the heavy lever 18. The hand wheel serves to rock the bell crank 43 and thereby vary the effective length of the link 23 and the degree of pressure applied between the head and the buck.

Steam under pressure from any suitable source is delivered by an inlet pipe 50 mounted upon shaft 19 to a branch 51 to the press head, re-

turning by pipe 52 through a discharge pipe 53, similarly supported at the other end of the shaft 18. A valve assembly 54 mounted on the head controls the discharge of steam from the hollow interior thereof through the padding on the head, the discharge being permitted when the valve stem 55 is raised by upward swinging movement of the lever 56 having a handle 57 associated therewith, the lever being normally held in the lowermost, valve-closing position by a spring 58.

In presses of the type referred to, pedal-actuated means for controlling the operations of the steam valve have been provided, in addition to the manual control by handle 57. In accordance with the prior practice (Figs. 7 and 8), a foot pedal 60, pivoted on the transverse shaft 38 is connected by a link 61 to a bell crank 62, the other arm of which is connected by an upwardly extending link 63 to a second bell crank 64, pivoted at 65 adjacent the upper ends of the frame members 15, 16. In such prior machines, the upwardly extending arm of the bell crank 64 is directly connected by a link to the down-turned end 68 of a bent lever 69, carrying a transverse bridge 70, underlying the end of the lever 56 so that when the lever 69 is swung about its pivot 71, the lever 56 is raised, thereby permitting the steam valve to open.

In accordance with the present invention, the upwardly extending arm of the bell crank 64 is elongated by the attachment thereto of an extension piece 66, and a link 67 connects the same to the lower end 68 of the bent lever 69, whereby the valve may be operated under pedal control as previously.

Certain presses of the type referred to above are provided with means for removing the steam and drawing air through the press buck, to cool garments pressed thereon, said means comprising a conduit 75 (Fig. 9) leading from the buck through a valve casing 76 and a pipe 77 to a suitable source of suction, such as a vacuum tank or the like, not shown. A vacuum valve 78 mounted on a horizontally reciprocable stem 79 is adapted to be closed by a spring 80 upon a valve seat 81, to cut off the suction and to terminate the flow of air through the buck. A bell crank 82, pivoted at 83 on a bracket 84 carried by the valve casing 76, has a bifurcated upper end 85 straddling the stem 79 and positioned behind a cap 86 thereon. The other end 87 of the bell crank is connected to a downwardly extending link 88, connected at its lower end to the rear end of a rock arm 89 fast on the transverse shaft 38 and adapted to be operated by a foot pedal 90. Hence, when the pedal 90 is depressed, the bell crank 82 is rocked in a clockwise direction, to open the valve 78 against the force of the compression spring 80.

The parts so far described, with the exception of the extension 66 on the lever 64, are standard features of construction of presses of the type referred to above and are not by themselves part of the present invention, except insofar as they are combined with the elements of the invention now to be described.

As stated above, the present invention provides power-operated means, preferably a plurality of solenoids, for operating the steam valve and the vacuum valve and for releasing the press head locking toggle system. It must be understood, of course, that in its broader aspects, the invention is not limited to the use of solenoids as other types of prime movers may be substituted.

As shown in Figures 3, 4, 8 and 8a, the upward-

ly projecting frame member 16 carries a Z-shaped bracket 95 having its lower end secured to the frame, with a horizontally projecting portion 96 overlying the upper end thereof, and a vertically projecting web 97 thereabove. A pair of spaced channel members 98, 99 secured to the web 97 carry a solenoid 100 and a pivot pin 101 for a lever 102, one end of which is connected at 103 to the armature 104 of the solenoid and the other end of which is connected by links 105 to the upper end 106 of the extension 66 secured to the pedal controlled steam valve-operating lever 64. It should be noted that the upper end of the lever 66 is laterally bent as at 107 to bring it into alignment with the solenoid-operated elements and that the pin 108 connecting the link 67 to the lever 66 is disposed in a rearwardly and upwardly inclined slot 109, thereby permitting the connection to shift when the press head is opened as indicated in Figure 8.

It will be apparent that, when the solenoid is energized and the armature 104 thereof is pulled downwardly, the lever 102 will rock in a counter-clockwise direction, thereby rocking the lever 66 in the same direction and lifting the steam valve controlling lever 68, to open the steam valve. When the solenoid is deenergized, the spring 58, associated with the valve, will close the same in the normal manner.

A similar solenoid is provided for controlling the operations of the vacuum valve. Referring to Figures 9, 9a and 9b, the cap 86, carried by the valve stem 79, has a pair of forwardly projecting legs 110 connected by a pin 111 to a pair of parallel links 112 which are connected at their forward ends by a pin 113 to a lever 114, pivoted to a pin 115, carried by channel members 116, 117 secured to a bracket plate 118 carried by the machine frame 12. A solenoid 120, carried by the channels 116, 117, has an armature 121 connected by a pin 122 to the free end of the lever 114. Hence, when the solenoid is energized and the armature thereof pulled downwardly, the lever 114 will be rocked in a clockwise direction to pull the valve stem 79 toward the right and open the valve against the compression of the spring 80. When the solenoid is deenergized, the spring will close the valve in the normal manner.

Novel power means are provided for releasing the head closing and locking toggle linkage system. Preferably, this means comprises a rock shaft 125 (Figs. 3-6) journalled in a bearing 126 carried by the rear face of the frame member 16 and having on one of its ends a projection or cam piece 127, overlying the upper surface of one of the toggle links 25 when the latter is in locked position. The other end of the rock shaft 125 carries a rock arm 128 connected by a pin 129 to a pair of downwardly projecting links 130, connected at their lower ends by a pin 131 to a short link 132 which is attached at its lower end to the armature 133 of a solenoid 134 carried by a bracket or box 135 mounted on the side face of the frame member 16.

From the construction just described it will be apparent that when the solenoid 134 is energized and the armature 133 pulled downwardly, the links 132 and 130 will draw the rock arm 128 downwardly, thereby turning the rock shaft 125 in a clockwise direction. This movement will be transmitted by the projection or cam piece 127 to the toggle link 25, thereby forcing the joint 32 thereof to move downwardly below dead center position. As a result of this movement, both

toggle are able to collapse under the influence of the weight 21 and the spring 38, thereby permitting the press head to open.

As explained below, in connection with the means for controlling the circuits of the several solenoids, the invention includes one or more switches which are actuated by opening and closing movements of the press head. Before describing the timer circuits and the like, a preferred mounting means and actuating means for the press head controlled switches will be described.

As shown in Figures 3, 4, 6 and 6a, the bracket 95 supported from the frame member 18 and which carries the steam valve operating solenoid 15 assembly, also supports a vertical plate 140, upon which one or more switches 141, 142 are supported. These switches are preferably of the Mu type, such as are manufactured by Mu-Swift Corporation, Canton, Massachusetts, under United States Patent No. 1,780,758, November 4, 1930. In the arrangement shown in connection with the first form of timer, described below, one of said switches is a single-pole, single-throw normally open switch, and the other is a single-pole, double-throw switch. These switches include operating plungers 143, adapted to cause a positive snap action of the switch elements under the influence of extremely light pressures applied thereto. Spring arms or feelers 144, 145, carried by the switches, are positioned to apply such pressure to the plungers under the influence of a bar 146, disposed therebelow and connected to a lever 147, the latter being pivoted at 148 to the supporting plate 140. A block 149, carried by the press head supporting lever 18, moves upwardly when the press head is closed, to engage and lift the lever 147 and bar 146, thereby raising the spring members 144, 145 and applying pressure to the plungers 143, to actuate the switches 141, 142. By appropriately bending or otherwise shaping the members 144, 145, one switch can be caused to shift slightly in advance of the other, upon opening and closing movements of the press head, which is a feature of utility as pointed out below.

One preferred form of timer for controlling the delivery of current to the solenoids successively for predetermined times in a predetermined cycle will now be described. The timer is preferably housed within a casing 155 (Figs. 1 and 10) secured to the side of the upstanding frame member 11 and includes a panel 156 upon which the various elements are mounted. The timer consists essentially of three time delay relays 157, 158 and 159, a pair of magnetically operated double-pole, single-throw relays 160, 161 mounted behind the panel, and suitable connections described below by reference to Figure 11. Each time delay relay is preferably of standard construction of a type that may be purchased on the market, and comprises a switch unit, for instance, of the Mu type referred to above, and a contact actuating mechanism driven in one direction by a self-starting synchronous motor, operated by alternating current, and reset by movement in the opposite direction under the influence of a coil spring. Time delay relays of this type are manufactured by the R. W. Cramer Company, Inc., Centerbrook, Connecticut and Paragon Electric Company, Chicago, Illinois and include a synchronous motor and automatic clutch manufactured by Haydon Mfg. Co., Forrestville, Connecticut. As shown in Figures 11a and 11b, a shaft 150 projecting through field members 151 carries

an aluminum armature 152 on one end and a pinion 153 on its other end, normally maintained out of mesh with the first gear of a gear train 154 by a spring 154a. When the field is energized, the armature and shaft are drawn toward the right by magnetic force against the force of spring 154a, as shown in dotted lines, to establish driving relation between the gears. The parts remain in this position until the motor is deenergized, whereupon the armature shaft is shifted to the left by the spring, to disengage the gears and to permit the train of gears to be rotated in the reverse direction under the influence of the coil spring referred to above. Each time delay relay includes a pointer 162 adapted to be moved over a scale marked off in seconds and fractions thereof to predetermined adjusted position by a micrometer screw 163. The contact actuating mechanism in the timer casing moves with the pointer, subject to the influence of the reset coil spring which tends to move the same in a clockwise direction as viewed in Figure 10. When current is delivered to the synchronous motor of the timer, the contact actuating mechanism rotates in a counter-clockwise direction from a position corresponding to the setting of the pointer 162 to the zero position, whereupon the switch is actuated and held in the actuated position by stalling of the synchronous motor and the continued engagement of the magnetically-operated gear clutch. When the delivery of current to the synchronous motor is interrupted, the armature shaft 152 is shifted by spring 154a and the gear clutch disengaged.

As pointed out below, the switches associated with the time delay relays 157 and 158 are of the single-pole, double-throw type, and that associated with relay 159 is of the single-pole, single-throw normally closed type. The relays 160, 161 are normally open double-pole, single-throw relays, well understood in the art.

Referring to Figure 10, the circuit includes a main line switch 165 delivering current to lines L1, L2, an operator-controlled starting button 166 adapted to close contacts 167, 168, two double-pole, single-throw relays 160, 161, two press head operated switches 141, 142, three time delay relays 157, 158, 159 and solenoids 100, 120 and 134. The elements in Figure 10 are all shown in their normal, deenergized position with the press head open. If the line switch 165 is closed and the press head moved to closed position, the switch 141 is closed and the switch 142 shifted, breaking the connection between contacts 171, 172 and establishing connection between contacts 173 and 174. If the starting button 166 is closed with the parts in this position pressed, current flows from L1 through contacts 167, 168, switch 141, through the coil 160' of relay 160, through line 175, and through the normally closed contacts 159a, 159b of the time delay relay 159 to the return line L2. This current flow energizes the coil 160' and closes the contacts 161a, 161b and the contacts 161c, 161d, the latter serving to shunt the push button and closing a holding circuit to maintain the coil 160' energized. Closing of the contacts 161a, 161b delivers current through line 185 to the synchronous motor 157' of the time delay relay 157, thereby initiating its operation. Simultaneously, current is delivered through branch lines 186, 187 and normally closed contacts 157a, 157b to the steam valve solenoid 100, thereby opening that valve and causing a delivery of steam to the press head.

After a predetermined time, the relay 157

switches over, to break the connection between contacts 157a, 157b and to establish connection between contacts 157c and 157d thereof, thereby deenergizing the steam valve solenoid 100 and delivering current by line 187 to the synchronous motor 158' of the second time delay relay 158. Since the motor of the first time delay relay 157 is still energized, the relay will not yet be reset to its initial starting position, but will maintain connection between 157c, 157d. Simultaneously with the delivery of current to the synchronous motor 158', current is delivered by line 187 to and through the normally closed contacts 158a, 158b to the vacuum valve solenoid 120, thereby opening the vacuum valve and subjecting the 15

buck to a flow of cooling air.

rent to the motor 200 is interrupted and the magnetically operated gear clutch associated therewith is simultaneously disengaged. It will be understood that the motor 200 is similar to the synchronous motor employed in the time delay relays described above and drives the shaft 201 at a constant, slow speed in a clockwise direction when energized.

The disc 202 carries a stop 205 adapted, upon 10 reverse, reset rotation under the influence of band 203 and spring 204 to engage a stationary abutment 206, to maintain the disc in the normal starting position. The disc also is provided with a plurality of circumferentially arranged apertures 207, adapted to receive pins 208 for timing the operations of the press, the pins being insertable in any holes desired for purposes of adjusting those operations.

A switch G, pivotally supported upon pins 208 20 adjacent the timing disc, is provided with a feeler 210 adapted to be swung downwardly into the path of movement of the timing pins 208 by a link 211, connected to the magnetic relay F, described below. When the switch G is swung to the operative position, the feeler 210 is contacted 25 periodically by the pins 208, thereby closing the switch G and controlling the operations of the solenoids associated with the press by the relay circuits shown in Figure 13. The switch G is preferably of the highly sensitive, snap-action type, such as the Mu switch 141 described above.

The circuit includes six electro-magnetic relays as follows; relay A comprising three poles 30 adapted to control five pairs of contacts A1, A2, A3, A4, A5; relay B comprising two poles adapted to control three pairs of contacts B1, B2, B3; relay C comprising three poles adapted to control four pairs of contacts C1, C2, C3, C4; relay D comprising three poles adapted to control five 35 pairs of contacts D1, D2, D3, D4, D5; relay E comprising a single-pole, single-throw switch adapted to control contacts E1; and relay F comprising a double-pole, single-throw switch adapted to control two pairs of contacts F1, F2. The circuit further includes a normally open, single-pole, single-throw switch 141 adapted to be closed 40 by a closing movement of the press head, in the same manner as the corresponding switch described above, and a similar starting button 166.

In the operation of the circuit shown in Figure 13, closing of the press head control switch 141 and the starting button 166 establishes a flow of current from L1 through line 215, normally closed contacts E1, line 216, switch 141, coil relay F, push button 166 to L2. Closing of contacts F1 holds relay F closed, shunting out push button 166. Closing of contacts F2 permits current to flow from L1 through line 215 to the Haydon motor 200 for return to L2 through contacts F2 and initiates operation of the timer disc 202. Simultaneously, current flows from L1 through normally closed contacts A5 of relay A to the steam valve solenoid 100 and returns from that solenoid through lines 217, 218 to the closed contacts F2 and L1, thus opening the steam valve.

When the first pin 208 closes switch G, current flows from G through closed contacts A2, relay coil B and returns through lines 219 and 218, thereby causing relay B to operate. Contacts B1 complete a temporary holding circuit for relay B through switch G to line 219. Current flows from line 215 through line 220, contacts B3 and line 221 to the coil of relay A, returning by line 219, thereby operating relay A.

Contacts A5 open, thereby interrupting the

After a predetermined time, the time delay relay 158 switches over, thereby breaking the connection between contact 158a, 158b, deenergizing the vacuum solenoid 120 and making connection between contacts 158c and 158d. The latter delivers current through line 188 to the coil 161' of relay 161, thereby closing the contacts thereof. The first pair of contacts 161a, 161b simply serve to shunt out the press head controlled switch 144, to continue the delivery of current to the coil 160' of the first relay 160 when the press head opens. The second pair of contacts 161c, 161d of the relay 161 deliver current through a line 189 to the synchronous motor 159' of the third time delay relay 159.

A branch line 190 leading from the line 188 delivers current through contacts 173, 174 of switch 142 to the head lock release solenoid 134, thereby energizing the same and opening the press.

As the press head opens, the switch 142 is shifted to its initial position, shown in Figure 11, thereby opening the circuit to the solenoid 134 and closing a circuit including lines 188, 190, contacts 171, 172 and line 191 to again energize the vacuum solenoid 120, and open the vacuum valve with the press head open and to subject the garment to another vacuum treatment.

The time delay relay 159, after a predetermined time, switches to open position, thereby breaking the connection between contacts 159a, 159b and deenergizing coil 160' of the first double-pole, single-throw relay 160, opening contacts 160a, 160b and contacts 160c, 160d. This interrupts the flow of current to the synchronous motors 157', 158' and 159' of the three time delay relays, whereupon they are automatically reset to their initial starting positions. Simultaneously, the coil 161' of the relay 161 is deenergized, to return that relay to its original position. The parts are now in position for the start of the next cycle of operation.

In the event that the operator opens the press head, for one reason or another, prior to the automatic operation thereof, the switch 141 is opened, thereby deenergizing the solenoid 160' and opening the connection between contacts 160a, 160b, with the result that the flow of current to the synchronous motors of the time delay relays is interrupted, causing them to be automatically reset to their initial starting positions.

In Figures 12 and 13, a second form of timer is disclosed, wherein a synchronous motor 200 of the type known in the trade as a Haydon motor is connected by magnetic clutch means when energized to drive a shaft 201 having a timing disc 202 fast thereon. A band 203 wound about the shaft and connected to a tension spring 204 serves to rotate the shaft in a reverse direction, to reset the timing disc when the delivery of cur- 75

flow of current through the steam valve solenoid 100. Contacts A4 close, thereby delivering current through line 222 and normally closed contacts D5 to the vacuum valve solenoid 120, returning by lines 217, 218, thereby opening the 5 vacuum valve.

Contacts A3 are closed without immediate effect, while contacts A1 complete a holding circuit for relay A through line 219.

Switch G, which has been closed only momentarily, now opens, thereby unlocking relay B and permitting the same to return to its original position.

Upon continued rotation of the timer disc 202, the second pin 208, after a predetermined interval, again closes the switch G, whereupon current flows through contacts A3, B2, C2 and the coil of relay D returning by lines 219 and 218. This operates relay D, with the result that the contacts D1 are closed, thereby completing a temporary holding circuit for relay D through switch G. Contacts D3 are closed, thereby establishing a flow of current from line 215 through line 225, contacts D3, line 226, the coil of relay C and return lines 219, 218. Simultaneously, contacts D5 are opened, thereby deenergizing the vacuum valve solenoid 120. Also, contacts D4 are closed, thereby energizing the head opening solenoid by a flow of current through A4, line 222, contacts D4, line 227 and return lines 217, 218. Opening of the press head under the influence of solenoid 134 opens switch 141. Before that can happen, however, relay C, energized as explained above, operates to close contacts C4, thereby shunting out the switch 144 and maintaining the coil of relay F energized by a flow of current from L1, line 215, contacts E1, line 228, contacts C4 and line 229. Contacts C1 are also closed, completing a locking circuit for the coil of relay C, from line 215 through branch 230, contacts C1, relay coil C and return lines 219, 218.

After being momentarily closed for a sufficient time to permit operation of relays D and C, switch G again opens, thereby unlocking relay D and permitting the same to return to its normal position. The latter movement of relay D opens the connection between contacts D4, thereby deenergizing the head opening solenoid 134 and closing contacts D5, to again energize the vacuum valve solenoid 120 as previously explained.

After the timer has rotated a predetermined number of degrees, the switch G is again closed, establishing a flow of current through G, A3, B2, C3, D2, coil of relay E and return lines 219, 218. This operates relay E to open contacts E1, thereby opening the circuit for the coil of relay F, permitting the same to return to its original, open position. This opens contacts F2, cutting off the supply of current to the Haydon motor 200 and deenergizing the coils of relays A, C and E, whereupon the timing disc 200 is returned to its original position by the spring 204 and coil 203 and all of the relays are returned to their original positions.

When relay F is energized, at the start of a cycle, link 211 is lifted by the armature thereof, thereby moving the feeler 210 into operative position. At the end of a cycle, when the relay F is deenergized, the link 211 is drawn downwardly, thereby swinging the feeler 210 upwardly, out of the path of movement of pins 208, so that the feelers will not be in position to retard or prevent movement of pins 208 during the reset rotation of the disc 202.

In the event that the press head is opened manually at a premature point in the cycle, the head operated switch 141 will be opened, to interrupt the circuit for the coil of relay F, thereby opening contacts F1 and F2 and returning all of the parts to their original positions, as described above.

The form of the invention shown in Figures 14-16 differs from that just described in that, instead of providing a plurality of electro-magnetically operated relays adapted to be operated successively by a single cam-operated switch, a plurality of cams and cam-operated switches are employed. A Haydon motor 300, which may be identical to the one described above, is employed to rotate a shaft 301 having four discs fast thereon, indicated at 302, 303, 304 and 305. The marginal portions of the discs are cut back, to provide circumferentially extending shoulders 306, beyond which a plurality of circumferentially arranged apertures 307 are formed. Outwardly projecting cam members 302a, 303a, 304a and 305a are secured upon the shouldered portions of the discs by bolts or pins extending through the apertures, the cam members being circumferentially adjustable by inserting the pins into different apertures. The shaft 301 and the discs carried thereby are adapted to be returned to their initial, starting position by a tension spring 310 and a coil 311, wrapped about the shaft, when the clutch associated with the synchronous motor 300 is disengaged by deenergizing the motor and the clutch controlling magnetic means.

A bracket 312, pivotally supported on pins 313 above the cam discs, carries a plurality of switches W, X, Y, Z, similar to the switch G described above, and having feelers 315, 316, 317 and 318, respectively, positioned to be engaged by the cams to operate the switches as hereinafter described. A link 320 connected to the bracket 312 serves to swing the feelers downwardly into operative position when the timer is set in operation, and to swing them in the opposite direction upon termination of its operation, so that the feelers clear the path of return movement of the cams.

As shown in Figure 16, the circuit of this timer comprises a double-pole, single-throw relay R, a normally open switch 141 adapted to be closed by closing movement of the press head, as described above, a starting button 166, and the cam controlled switches W, X, Y, Z. Switches W and X are single-pole, double throw Mu switches, switch Y is a single-pole, single-throw normally closed Mu switch, while switch Z is a similar single-pole, single-throw normally open switch.

In the operation of this circuit, if the head control switch 141 and the starting button 166 are closed, current flows from line L1 through 60 166, the coil of relay R, switch 141 and contacts Y1 to L2, thereby operating relay R and closing contacts R1 and R2. Contacts R1 complete a holding circuit for the coil of the relay and maintain the same closed. Contacts R2 deliver current to the Haydon motor 300 and starts the cam discs rotating. Simultaneously, current is delivered through line 325, contacts W2 to the steam valve solenoid 100, to deliver steam to the press head. After a predetermined time, (Figs. 15a and 15b) the cam 302a comes in contact with feeler 315, to operate switch W, thereby opening contacts W2 and closing contacts W1, with the result that the steam valve solenoid 100 is deenergized and the vacuum valve solenoid 120 ener-

gized by a flow of current through contacts W_1 and X_2 .

After a predetermined time, the cam projection $305a$ lifts feeler 318 , thereby closing contacts Z_1 of switch Z and shunting out the press head control switch 141 , to maintain the coil of solenoid R energized. A fraction of a second after this occurs, the cam projections $303a$ raises feeler 316 and operates switch X , thereby opening contacts X_2 to deenergize the vacuum solenoid 128 and closing contacts X_1 to energize the head lock release solenoid 134 . It will be noted that the cam $303a$ is quite short in its circumferential extent, so that the switch X almost immediately returns to its original position, deenergizing the head opening solenoid 134 as soon as the latter has performed its function and again energizing the vacuum solenoid, to subject the buck to the influence of a vacuum with the press head open.

The parts remain in this condition until the cam $304a$ raises the feeler 317 , thereby opening the normally closed contacts Y_1 of switch Y and interrupting the circuit for the coil of relay R . Contacts R_1 and R_2 open, deenergizing the Haydon motor 300 and permitting the timer discs to be returned to their original position by spring 318 and coil 311 .

The link 320 connected to the frame 312 for the several switches $W-Z$ is connected to the armature of relay R , in such manner that, when the relay is energized at the commencement of a cycle, the link 320 is lifted, thereby swinging the feelers $315-318$ downwardly into the path of movement of the cams carried by the cam discs. When the relay R is deenergized, the link 320 is lowered to swing the feelers $315-318$ upwardly, out of the path of movement of the cams, so that the switches will not be operated upon reverse rotation of the cams during the resetting operation.

If the press head control switch is opened prematurely, by opening the head, the circuit for the coil of relay R will be similarly opened by switch 141 , thereby again permitting the parts to return to their original positions.

It is thought that the structure and mode of operation of the three preferred embodiments of the invention will be entirely clear to those skilled in the art from the foregoing description. In all cases, the setting of the timer may be adjusted at the will of the operator, to vary the time in each cycle of each particular operation, so that great flexibility of operations is accomplished. In the first form of the invention, the adjustment is effected by simply changing the positions of one or more, or all of the pointers 162 , while in the last two forms, the pins 208 and the cam pieces $302a-305a$ may be shifted circumferentially of the timer shaft to accomplish the same result. When once adjusted, the timer is effective to make the press operate through an indefinite number of identical cycles, until the adjustment is changed for one reason or another.

Although the invention has been described with considerable particularity in the foregoing specification and by reference to the accompanying drawings, it must be understood that the invention is not limited to these specific details, but covers all modifications coming within the scope of the appended claims and their equivalents.

I claim:

1. Apparatus for automatically controlling the operations of a garment press of the type comprising a buck, a movable head, locking means for holding the head closed upon the buck, a

steam valve, a vacuum valve, power-actuated means for operating said valves and for releasing the press head, automatic means for controlling the operations of said power-actuated means in a normal cycle, operator-actuated means for releasing the press head at any desired time prior to completion of a normal cycle, means for rendering said automatic means and said power-actuated means inoperative upon operation, prior to completion of a normal cycle, of said operator-actuated press head releasing means, and means for automatically resetting said automatic means to the normal starting position either upon completion of a normal cycle or upon interruption of a normal cycle by premature operation of said operator-actuated press head releasing means.

2. A garment pressing apparatus comprising a buck, a movable head, locking means for holding the head closed upon the buck, a steam valve, a vacuum valve, power-actuated means for operating said valves and for releasing the press head, operator-actuated means operable at any desired time for releasing the press head, and an automatic timer for controlling the operations of said power-actuated means in a predetermined cycle, said timer comprising means movable from a normal starting position, means actuated thereby for successively operating said power-actuated means, and means for automatically resetting said movable means to said normal starting position upon completion of the normal cycle or upon interruption thereof by such premature operation of the press head releasing means.

3. A timing apparatus for automatically controlling a garment press of the type comprising a buck, a movable head, a lock for holding the head closed upon the buck, a steam valve, a cooling-fluid valve and operator-actuated means for releasing said head lock, said timing apparatus comprising time controlled means operable from a starting position for successively and automatically controlling the operations of the valves and the head lock in a desired pre-determined cycle in which the valves are opened and closed successively and the head lock release is actuated to open the press, and means for rendering said time-controlled means inoperative and for automatically re-setting the same to its original starting position upon operation of said operator-actuated head lock releasing means prior to the normal release of the head lock during the automatic cycle of operations.

4. A timing apparatus for automatically controlling a garment press of the type comprising a buck, a movable head, a lock for holding the head closed upon the buck, a steam valve, a vacuum valve and operator-actuated means for releasing said head lock, said timing apparatus comprising a plurality of solenoids connected respectively to release said head lock, to open and close said steam valve and to open and close said vacuum valve, time controlled means for automatically and successively operating said solenoids in a predetermined normal cycle, and means for automatically returning said time controlled means to the original starting position upon completion of said normal cycle.

5. A timing apparatus for automatically controlling a garment press of the type comprising a buck, a movable head, a lock for holding the head closed upon the buck, a steam valve, a vacuum valve and operator-actuated means for releasing said head lock, said timing apparatus comprising a plurality of solenoids connected respectively to release said head lock, to open and

close said steam valve and to open and close said vacuum valve, time controlled means for automatically and successively operating said solenoids in a predetermined, normal cycle, and means for automatically returning said time controlled means to the original starting position upon completion of said normal cycle or upon premature release of said head lock by said operator-actuated means.

6. A timing apparatus for automatically controlling a garment press of the type comprising a buck, a movable head, a lock for holding the head closed upon the buck, a steam valve, a vacuum valve and operator-actuated means for releasing said head lock, said timing apparatus comprising a plurality of solenoids connected respectively to release said head lock, to open and close said steam valve and to open and close said vacuum valve, time controlled means for automatically and successively operating said solenoids in a predetermined, normal cycle to open and close the steam valve, to open and close the vacuum valve, to release said head lock and to again open and close said vacuum valve, and means for automatically returning said time controlled means to the original starting position upon completion of said normal cycle or upon premature release of said head lock by said operator-actuated means.

7. A timing apparatus for automatically controlling a garment press of the type comprising a buck, a movable head, a lock for holding the head closed upon the buck, a steam valve and a vacuum valve, said timing apparatus comprising a solenoid for operating the steam valve, a solenoid for operating the vacuum valve, a solenoid for releasing said head lock, time controlled means movable from a normal starting position through a predetermined cycle to energize the first solenoid for a predetermined period to open and then close the steam valve, then to energize the second solenoid for a predetermined period to open and then close the vacuum valve, then to momentarily energize the third solenoid to release the head lock, then to again energize the second solenoid for a predetermined period to open and then close the vacuum valve with the press head open, and means for automatically returning the time controlled means to the said normal starting position upon completion of said predetermined cycle.

8. A timing apparatus for automatically controlling a garment press of the type comprising a buck, a movable head, a lock for holding the head closed upon the buck, a steam valve, a vacuum valve and operator-actuated means for releasing said head lock, said timing apparatus comprising a solenoid for operating the steam valve, a solenoid for operating the vacuum valve, a solenoid for releasing said head lock, time controlled means movable from a normal starting position through a predetermined cycle to energize the first solenoid for a predetermined period to open and then close the steam valve, then to energize the second solenoid for a predetermined period to open and then close the vacuum valve, then to momentarily energize the third solenoid to release the head lock, then to again energize the second solenoid for a predetermined period to open and then close the vacuum valve with the press head open, and means for automatically returning the time controlled means to said normal starting position upon completion of said predetermined cycle or upon release of said head lock by said operator-actuated means.

9. A timing apparatus for automatically con-

trolling a garment press of the type comprising a buck, a head movable to closed position thereon, a lock for holding the head in the latter position, a steam valve and a vacuum valve, said apparatus comprising solenoids for operating said valves and for releasing said head lock, an electric circuit for said solenoids, time controlled means in said circuit for energizing the solenoids successively in a predetermined cycle, a circuit closer in said circuit, and means operated by closing movement of the press head for closing said circuit closer.

10. A timing apparatus for automatically controlling a garment press of the type comprising a buck, a head movable to closed position thereon, a lock for holding the head in the latter position, a steam valve and a vacuum valve, said apparatus comprising solenoids for operating said valves and for releasing said head lock, a circuit for said solenoids, time controlled means for said circuit for energizing the solenoids successively in a predetermined cycle, a press head operated switch in said circuit permitting initiation of the cycle only when the press head is closed, and another switch connected in the circuit to shunt the press head operated switch to permit continuation of the cycle after the press head opens.

11. A timing apparatus for automatically controlling a garment press of the type comprising a buck, a head movable to closed position thereon, a lock for holding the head in the latter position, a steam valve and a vacuum valve, said apparatus comprising solenoids for operating said valves and for releasing said head lock, an electric circuit for said solenoids, time controlled means in the circuit, a press head operated switch in the circuit to initiate operation of the time controlled means and to energize the steam valve solenoid only when the head is closed, means actuated by said time controlled means for deenergizing the steam valve solenoid after a predetermined time and for simultaneously energizing the vacuum valve solenoid, means actuated by said time controlled means for deenergizing the vacuum valve solenoid after a predetermined time and for simultaneously energizing the head lock releasing solenoid, another switch connected in said circuit for shunting said press head operated switch when the head opens under control of the last-mentioned solenoid and for again energizing the vacuum valve solenoid, and means actuated by said time controlled means for deenergizing the vacuum valve solenoid.

12. A timing apparatus for automatically controlling a garment press of the type comprising a buck, a head movable to closed position thereon, a lock for holding the head in the latter position, a steam valve and a vacuum valve, said apparatus comprising solenoids for operating said valves and for releasing said head lock, an electric circuit for said solenoids, time controlled means in the circuit, a press head operated switch in the circuit to initiate operation of the time controlled means and to energize the steam valve solenoid only when the head is closed, means actuated by said time controlled means for deenergizing the steam valve solenoid after a predetermined time and for simultaneously energizing the vacuum valve solenoid, means actuated by said time controlled means for deenergizing the vacuum valve solenoid after a predetermined time and for simultaneously energizing the head lock releasing solenoid, another switch connected in said circuit for shunting said press head operated switch when the head opens under control of the last-

mentioned solenoid and for again energizing the vacuum valve solenoid, means actuated by said time controlled means for deenergizing the vacuum valve solenoid, and means for resetting said time controlled means to the initial starting position.

13. For use with a garment press of the type comprising a buck, a head movable to closed position thereon, a lock for holding the head in the latter position, a steam valve and a vacuum valve; a timing apparatus for controlling said valves and release of the head lock, comprising solenoids for the valves and the head lock release, electric circuits for the solenoids, time controlled switches in the circuits for energizing and deenergizing the solenoids successively in a predetermined cycle, and a pair of switches operated by closing and opening movements of said head, one serving to initiate operation of the time controlled switches and of the cycle only when the head is closed and the other serving to continue a portion of the cycle when the head opens under actuation of the head lock release solenoid.

14. A timing apparatus for automatically controlling a garment press of the type comprising a buck, a head movable to closed position thereon, a lock for holding the head in the latter position, a steam valve, a vacuum valve and operator actuated means for releasing said head lock, said apparatus comprising solenoids for operating said valves and for releasing said head lock, electric circuits for said solenoids, circuit controlling means for said circuits, synchronous electric motor means for moving said circuit controlling means from a normal starting position through a normal cycle, and means for automatically resetting said circuit controlling means to the normal starting position upon completion of a normal cycle or upon opening of the press head by said operator-actuated head lock releasing means.

15. A timer for automatically controlling a garment press of the type comprising a buck, a head movable to closed position thereon, a lock for the head, a steam valve and a vacuum valve, said apparatus comprising solenoids for operating said valves and for releasing said head lock, circuits for said solenoids, and means for controlling said circuits, said last-mentioned means comprising a plurality of adjustable time delay relays for the circuits and connections for the relays so arranged that one relay initiates operation of another after a predetermined time, and means for resetting all of said time delay relays upon completion of a normal cycle.

16. An apparatus for controlling a garment press of the type comprising a buck, a movable head, a lock for holding the head closed on the buck, a steam valve and a vacuum valve, said apparatus comprising solenoids for the valves and for releasing the head lock, a relay connected to deliver current to energize the steam valve solenoid, manual current control means for energizing said relay, a time delay relay connected to have its operation initiated by the first relay and to shift over after a predetermined time to deenergize the steam valve solenoid and to energize the vacuum valve solenoid, a second time delay relay connected to have its operation initiated by said shift-over of the first time delay relay and itself to shift over after a predetermined time to deenergize the vacuum valve solenoid and to energize the head lock release solenoid to permit the head to open, a switch actuated by opening movement of the head for again energizing the vacuum valve solenoid, a third

time delay relay connected to have its operation initiated by the shift-over of the second time delay relay and itself to shift over after a predetermined time to deenergize the first-mentioned relay, thereby deenergizing the vacuum valve solenoid and all of the time delay relays.

17. An apparatus for controlling a garment press of the type comprising a buck, a movable head, a lock for holding the head closed on the buck, a steam valve and a vacuum valve, said apparatus comprising solenoids for the valves and for releasing the head lock, and a timer for said solenoids comprising three time delay relays, a pair of double-pole, single-throw relays, a pair of press head actuated single-pole, single-throw switches, an operator actuated starting switch and electrical connections so arranged that closing of the last-mentioned switch energizes and closes the first of said double-pole, single-throw relays if the first press head actuated switch is closed, closing of said first relay serving to deliver current to the first time delay relay and to the steam valve solenoid, said first time delay relay after a predetermined time serving to interrupt the delivery of current to the steam valve solenoid and to deliver current to the second time delay relay and to the vacuum valve solenoid, the second time delay relay after a predetermined time serving to interrupt the delivery of current to the vacuum valve solenoid and to deliver current to the head lock release solenoid and to the second double-pole, single-throw relay to energize and close the same, said second relay when closed serving to shunt the first press head operated switch and to deliver current to the third time delay relay, the opening of said head resulting from energizing of the press head lock release solenoid serving to close the second press head operated switch and to again deliver current to the vacuum valve solenoid, the third time delay relay, after a predetermined time, serving to deenergize the first double-pole, single-throw relay and open the latter, thereby deenergizing all of the other relays.

18. An apparatus for controlling a garment press of the type comprising a buck, a movable head, a lock for holding the head closed on the buck, a steam valve and a vacuum valve, said apparatus comprising solenoids for the valves and for releasing the head lock, a member mounted for rotation from a predetermined normal starting position, means for slowly rotating the member at a constant speed, operator-actuated means for initiating rotation thereof, a master switch, a plurality of elements carried by said rotatable member for periodically and successively closing said switch at predetermined times, a plurality of relays connected to be operated successively by the successive closing of said master switch, connections from said relays to said solenoids adapted to energize the solenoids successively to open and close the steam valve, to open and close the vacuum valve, to release the head lock and to again open and close the vacuum valve, and means for returning said rotatable member to its normal starting position upon completion of a cycle of operations.

19. An apparatus for controlling a garment press of the type comprising a buck, a movable head, a lock for holding the head closed on the buck, a steam valve, a vacuum valve and operator-actuated means for releasing the head lock, said apparatus comprising solenoids for the valves and for releasing the head lock, a mem-

ber mounted for rotation from a predetermined normal starting position, means for slowly rotating the member at a constant speed, operator-actuated means for initiating rotation thereof, a master switch, a plurality of elements carried by said rotatable member for periodically and successively closing said switch at predetermined times, a plurality of relays connected to be operated successively by the successive closing of said master switch, connections from said relays to said solenoids adapted to energize the solenoids successively to open and close the steam valve, to open and close the vacuum valve, to release the head lock and to again open and close the vacuum valve, and means for returning said rotatable member to its normal starting position upon completion of a normal cycle of operations or upon interruption of such a cycle by operation of said operator-actuated head lock releasing means.

20. An apparatus for controlling a garment press of the type comprising a buck, a movable head, a lock for holding the head closed on the buck, a steam valve and a vacuum valve, said apparatus comprising solenoids for the valves and for releasing the head lock, a rotatable member, means for slowly rotating the same at a predetermined relatively slow constant speed, a plurality of cams carried by said member, a corresponding number of switches positioned adjacent the cams, circuits controlled by said switches for energizing and deenergizing the steam valve solenoid, the vacuum valve solenoid and the head lock release solenoid in a predetermined cycle controlled by said cams, and means for returning said rotatable member and said cams to their normal starting position upon completion of a normal cycle.

21. In a garment press having a steam valve, a vacuum valve, a head lock release and solenoids for actuating said valves and said release, a timer for controlling the delivery of current to said solenoids, comprising four cam controlled switches, a relay, a press head controlled switch, a starting button, a synchronous motor, switch controlling cams driven by said motor, and electrical connections whereby closing of said starting button energizes said relay when the press head controlled switch is closed, said relay serving to close a relay holding circuit and to deliver current to said synchronous motor and to the steam valve solenoid, the first to operate of said cam controlled switches serving to deenergize the steam valve solenoid and energize the vacuum valve solenoid, the next to operate of said cam controlled switches serving to shunt the press head controlled switch to maintain the relay energized when the head opens, the next to operate of said cam controlled switches serving to temporarily deenergize the vacuum valve solenoid and to energize the head lock release solenoid thereby to open the press head, the last

to operate of said cam controlled switches serving to deenergize the relay and thereby interrupt the current to the synchronous motor and the vacuum valve solenoid.

5 22. The combination with a garment press of the type comprising a buck, a vacuum conduit leading to the buck, a valve in said conduit including a movable stem, pedal-actuated means for operating said valve and including a lever connected to the valve stem, of power means for operating the valve, comprising a solenoid, a lever adapted to be rocked by said solenoid and a link connection between the lever and the valve stem, whereby the valve is opened when the solenoid is energized.

10 23. An apparatus for controlling a garment press of the type comprising a buck, a movable head, a lock for holding the head closed on the buck, a steam valve and a vacuum valve, said apparatus comprising solenoids for the valves and for releasing the head lock, a member mounted for rotation from a predetermined normal starting position and having a plurality of projections thereon, means for slowly rotating

20 25 the member in one direction through a normal cycle at a constant speed, circuit controlling means for the solenoids having feeler means adapted to be contacted by said projections, means for moving said feeler means into the path of movement of said projections upon initiation of rotation of the rotatable member, means for rotating the rotatable member in a reverse direction to the normal starting position at the end of the normal cycle, and means for moving said 30 35 feeler means out of the path of movement of said projections during such rotation in the reverse direction.

24. An apparatus for controlling a garment press of the type comprising a buck, a movable head, a lock for holding the head on the buck, a steam valve and a vacuum valve, said apparatus comprising solenoids for the valves and for releasing the head lock, a member mounted for rotation from a predetermined normal starting position and having a plurality of projections thereon, a synchronous electric motor for slowly rotating said member at a constant speed through a normal cycle, an operator controlled relay for energizing the synchronous motor and initiating 40 45 rotation thereof, circuit controlling means for the solenoids pivoted adjacent the rotatable member and having feeler means associated therewith, a connection from said relay to said circuit controlling means for moving said feeler means into the path of movement of said projections when the relay is engaged to start the synchronous motor, said connection serving to move the feelers out of said path when the relay is deenergized, and means for reversing the rotation 50 55 of the rotatable member when the relay and the synchronous motor are deenergized.

ROBERT J. RANDALL.
